DESIGN FOR A CONNECTOR PLUG

Carl H. Judisch, New Haven, Conn., assignor to
The Whitney Blake Company, New Haven,
Conn., a corporation of Connecticut

Application December 23, 1940, Serial No. 97,566

Term of patent 14 years

To all whom it may concern:

Be it known that I, Carl H. Judisch, a citizen of the United States, residing at New Haven, in the county of New Haven and State of Connecticut, have invented a new, original, and ornamental Design for a Connector Plug, of which the following is a specification, reference being had to the accompanying drawing, forming part thereof.

Fig. 2 is a side elevational view of the same.

Fig. 3 is an end elevational view of the same.

I claim:

The ornamental design for a connector plug, as shown.

CARL H. JUDISCH.
